UNITED STATES PATENT OFFICE.

BYRAM S. DICKERSON, OF MATTOON, ILLINOIS.

DRAFT GEAR FOR TRAINS.

Application filed August 4, 1922. Serial No. 579,747.

To all whom it may concern:

Be it known that I, BYRAM S. DICKERSON, a citizen of the United States, residing at Mattoon, in the county of Coles and State of Illinois, have invented certain new and useful Improvements in Draft Gears for Trains, of which the following is a specification.

This invention relates to draft gears for trains and the prime feature of the invention is the provision of means in connection with the draft appliances of a train for taking up slack or lost motion between the various units making up the train and for maintaining a certain resilient state while the train is in motion on a track of varying grades and during sudden changes in speed.

A further feature of the invention is in so constructing the parts of the device that the engine will start a heavy train without the necessity of gathering slack as is common, also to receive and cushion the impact of cars when colliding by virtue of the various resilient features embodied in the device.

25 A further feature of the invention is the provision of a draft gear arrangement that will transmit the energy of the draw bar force of the engine to the train and which will function in such a manner that the increasing momentum of the moving engine will be transmitted to the different units of the train in proportion to the resistance encountered, thus avoiding the development of destructive strains in the draft gear and car frame.

35 A further feature of the invention is the provision of a combined air and liquid cushioning means for receiving the various impacts, means being provided for gradually increasing the cushioning effect of the liquid incident to the termination of the movements of the parts directed against the fluid.

40 Other objects and advantages will be hereinafter more fully set forth and pointed out in the accompanying specification.

45 In the accompanying drawings,

Figure 1 is a detail longitudinal sectional view through a draft appliance, such as is used in connection with steam propelled or electric form of train equipment,

50 Figure 2 is a top plan view thereof,

Figure 3 is a detail longitudinal sectional view through a slightly modified structure,

55 Figure 4 is a similar view of a further modified structure,

Figure 5 is a detail sectional view of a

modified form of a similar construction used in connection with the remainder of the draft appliance,

60 Figure 6 is a similar view of a further modified construction,

Figure 7 is a detail sectional view of a lever operated mechanism, and

65 Figure 8 is a detail sectional view in which a bellows construction is used for receiving the air pressure.

Referring to the drawings in which similar reference numerals designate corresponding parts throughout the several views, 1 indicates a frame such as is commonly used 70 on railway engines and coaches and in said frame is slidably mounted the usual or any preferred form of draw bar 2, the inner end of which is connected to a head 3 attached to a carrier 4 which is slidably mounted 75 within the frame 1, the inner ends of the side members of the carrier being connected together by means of a block 5, the head 3 and block 5 spacing the side members of the carrier a distance apart. Attached to 80 the frame 1 on opposite sides of the block 5 are cylinders 6 and 7, the cylinder 6 having a piston 8 slidably mounted in one end thereof to which is connected a piston rod 9, said rod projecting through one end of the cylinder 6 and normally abuts against one face of the block 5. Fixed within the cylinder 6 is a partition wall 10 through which are formed ports 11 for the passage of liquid, such as oils or the like, when pressure is 85 applied against the liquid by the movement of the piston 8, said piston having cone-like projections 12 so arranged that before completion of the stroke of the piston they will enter the ports 11 and gradually cut off the 90 flow of the liquid therethrough and increase the pressure and cushioning effect of the liquid against the piston, and if desired the ports may be slightly tapered to conform 95 more or less to the contour of the projections 12. On the opposite side of the partition wall 10 from the piston 8 is an auxiliary piston 13 which also forms a separating movable wall between the two ends of the cylinder, and by introducing air under pressure into the compartment 14 formed by the auxiliary piston, resistance to the movement of the auxiliary piston will be set up 100 when pressure of the liquid is directed against the auxiliary piston through movement of the main piston 8, thereby providing 105 a combined air and liquid cushion for

the forward or backward movement of the carrier and parts associated therewith. The air may be obtained from any suitable source, but is preferably derived from the usual air line 15, commonly associated with trains of this nature, said air line having a valve 16 for preventing the discharge of the air from the compartment 14 when pressure is directed thereagainst, or when the 10 train air line is disconnected.

The cylinder 7 has a piston 17 therein similar to the piston 8, the piston rod 18 connected therewith extending through the end of the cylinder 7 and contacting with the block 5 on the opposite side thereof from the rod 9, consequently any inward or rearward movement of the carrier 4 will be directed against the rod 18 and piston 17. The cylinder 7 is also provided with a partition wall 19 through which are formed ports 20 similar to the ports 11, the piston 17 having substantially cone-shaped projections 21 for co-operation with said ports 20. On the opposite side of the partition 19 from the piston 17 is an auxiliary piston 22 which forms a compartment 23 at one end of the cylinder 7 to receive air under pressure, the air line 15 also being connected with the compartment 23. With this form of device 25 when forward movement is imparted to the train units to which the cylinders are connected pressure will be directed against the fluid within the cylinder 6 and the air within the compartment 14 of said cylinder, thereby eliminating sudden jars or strains on the parts of the train equipment, and owing to the pressure of the air within the cylinder, as soon as the pull of the draw bar is released, the expansion of the air within 30 the compartment 14 will return the liquid through the ports 11 and force the piston 8 towards the rear end of the cylinder 6 thereby taking up any slack that may occur incident to releasing the pull on the draw bar. This same action is true of the cylinder 7 and parts associated therewith, as when a rearward or inward thrust is given to the draw bar 2.

In Figure 3 of the drawings, all of the 35 parts of the device are similar except that individual cylinders 24 and 25 are provided for the air and associated with said cylinders are additional cylinders 26 and 27 for receiving the liquid, the pistons 28 and 29 in the cylinders 24 and 25 respectively having elongated piston rods 30 and 31 which project through the cylinders 26 and 27 and have auxiliary pistons 32 and 33 thereon which are slidable in the cylinders 26 and 27 when the rods 30 and 31 are moved lengthwise. Instead of having partitions in the cylinders through which ports are formed for the passage of the liquid, the walls of the cylinders 26 and 27 are provided 40 with tapered channels 34 and 35 respec-

tively, the taper of said channels being such that at the beginning of movement of the auxiliary pistons the liquid within the cylinders 26 and 27 will flow more or less rapidly to the rear of said auxiliary pistons, but as the pistons near the ends of their initial strokes the taper of the channels will gradually decrease or check the flow of the liquid. 70

In Figure 4 of the drawings, a pair of cylinders 36 and 37 are provided for the reception of a liquid and air respectively and in this construction the carrier 4 is dispensed with and a plunger 38 connected with the head 3, said plunger projecting through one end of the cylinder 36 and into a secondary cylinder 39 slidably mounted within the cylinder 36, the liquid within the cylinder 36 passing from end to end of the secondary cylinder as it is moved lengthwise by the plunger through elongated tapered channels 40 provided in the interior wall of the cylinder 36. 75

The secondary cylinder 39 has a piston rod 41 connected therewith which extends into the air cylinder 37 and is connected with a piston 42 so that when a forward pull is given to the plunger 38 the air within the cylinder 37 will be compressed. The secondary cylinder 39 is constructed similar to the cylinders 6 and 7 and has a partition wall 43 through which are formed ports 44 for the passage of the liquid from end to end of the secondary cylinder, the plunger 38 having a piston 45 which compresses the liquid within the secondary cylinder, said piston 45 having projections 46 for co-operation with the ports 44 for gradually cutting off the flow of liquid therethrough. On the opposite side of the partition 43 from the piston 45 is an auxiliary piston 47 which has sliding action within the secondary cylinder and is adapted to compress the air that is entered in one end of the secondary cylinder from the air cylinder 37, a passage 48 being formed through the piston rod 41 so that the air may readily enter the compartment 49 formed by the auxiliary piston 47, the escape of the air from compartment 49 being controlled by a valve 50. 115 The pistons within the secondary cylinder control and cushion the rearward thrust of the plunger 38 and parts associated therewith. 100

In Figure 5 of the drawings, a single cylinder 51 is provided which is divided into compartments 52, 53 and 54 by partitions 55 and 56, the partition 56 having ports 57 therethrough for the passage of liquid. The compartment 52 receives air under pressure 110 while the compartment 54 contains a liquid, and the compartment 53 receives both air and liquid, a piston 58 within the compartment 53 separating the liquid and air. A piston 59 is mounted in the compartment 125 130

52 and is connected with the piston 58 through a rod 60 so that both of said pistons will operate in unison. The compartment 52 and one end of the compartment 53 are connected by an air passage 61 so that air may enter from the compartment 52 into the compartment 53. Within the compartment 54 is a piston 62 which has a rod 63 connected therewith for engagement with the block 10 5 of the carrier 4. The piston 62 is provided with projections 64 which co-operate with the ports 57 for gradually checking the flow of the liquid through said ports as the piston 62 is moved lengthwise of the compartment 54.

The form of device shown in Figure 6 comprises a cylinder 65 in which is provided a partition 66 and on one side of said partition is a piston 67 having a piston rod 20 68 projecting through one end of the cylinder 65, this piston having projections 69 for co-operation with ports 70 formed through the partition 66. At the opposite side of the partition 66 from the piston 67 is an auxiliary piston 71 which forms a compartment 72 at one end of the cylinder 65 for the reception of air, a coil spring 73 being positioned between the end of the cylinder and the auxiliary partition 71 for assisting the air in cushioning the movement of the auxiliary piston.

The structure shown in Figure 7 of the drawings, comprises a pair of cylinders 74 and 75 which are in spaced relation with 35 each other, each having a piston 76 and 77 respectively, the rods 78 and 79 attached to said pistons having their free ends pivoted to a lever 80, one end of the lever 80 being pivoted to parts of the train structure.

40 The cylinder 74 is provided with a partition 81 through which are formed ports 82 for the passage of a liquid, a piston 83 being also mounted within the cylinder 74 at the side of the partition 81 opposite the piston 76, a piston rod 84 connected with the piston 83 being adapted to contact with the block 5. In this form of device when pressure is directed against the piston rod 84 the piston 76 will be moved lengthwise which will direct a thrust on the lever 80 and move the piston 77 lengthwise of the cylinder 75, both of the pistons 76 and 77 being directed against an air cushion.

In Figure 8 of the drawings, a cylinder 85 is provided, said cylinder having a partition 86 through which are formed ports 87 for the passage of a liquid, a piston 88 being slidably mounted in the cylinder at one side of the partition 87, the piston rod 89 connected therewith being adapted to contact with the block 5. On the opposite side of the partition 87 from the piston 88 is a bellows construction 90 which is adapted to receive air, the pistons 91 and 92 being attached to opposite ends of the bellows so

that when pressure is directed against the pistons the bellows will collapse and expand in the usual well known manner. In this form of device the bellows is also surrounded with a liquid, the wall of the cylinder 85 70 having one or more channels 93 therein which permits the fluid to pass on opposite sides of the piston 92 and thus allow the liquid to react against the bellows construction in such a manner as to relieve the flexible wall of the bellows air container 90 from strain due to the inner air pressure and at the same time allow it to expand and collapse freely as a bellows.

Having thus fully described my said invention, what I claim as new and desire to secure by Letters Patent, is:

1. In a draft gear for trains or the like, a stationary frame, a drawbar associated slidably with said frame, a stationary cylinder, a piston in said cylinder, means associated with said drawbar for moving said piston in one direction, means for confining a liquid within said cylinder and causing it to direct resistance against said piston in one direction, means for retarding and gradually stopping the flow of the liquid within said cylinder, means for utilizing air under pressure for increasing the resistance of the liquid against said piston, said air pressure also returning said piston to its initial position and holding the drawbar against sudden sliding displacement in either direction, and movable means separating said liquid and air. 100

2. In a draft gear for trains or the like, a stationary frame, a drawbar associated slidably with said frame, a stationary cylinder, a piston in said cylinder, means associated with said drawbar for moving said piston in one direction, means for confining a liquid within said cylinder and causing it to direct resistance against said piston in one direction, means for retarding and gradually stopping the flow of liquid within 110 said cylinder, and a closed flexible container adapted to change form and volume for confining air in said cylinder under pressure.

3. In a draft gear for trains or the like, a stationary frame, a draw bar slidably longitudinal of the frame, a carrier connected with said draw bar and movable therewith, a block at the inner end of said carrier, cylinders on opposite sides of the block, pistons in said cylinders co-acting with said block, means for confining a liquid within the cylinders and causing the same to direct resistance against said pistons in one direction, means for retarding and gradually stopping the flow of the liquid within the cylinders, and means for utilizing air under pressure for returning the pistons to their initial positions and for holding the draw bar against sudden sliding displacement in either direction. 120 125 130

4. In a draft gear for trains or the like, a stationary frame, a carrier slidably mounted in said frame having a head at one end and a block at the opposite end, a draw bar 5 fixed to and movable with said carrier, a pair of stationary cylinders, one at each side of said block, one portion of each cylinder being adapted to receive a fluid and another portion a cushion of air under compression, 10 a piston in the fluid receiving end of each cylinder, a piston rod extending from each piston and engaging said block on opposite sides, a partition in each cylinder having ports therethrough through which the liquid 15 may flow incident to movement of said pistons, means carried by the pistons for gradually reducing and cutting off the flow of the liquid through said ports, and an auxiliary piston in each cylinder adapted to compress the air in the cylinders when moved 20 in one direction and cause the liquid to return through said ports when moved in the opposite direction.
5. In a draft gear for trains or the like, a draw bar, a carrier connected with said draw bar, a connecting block at one end of said carrier, a cylinder on opposite sides of said block, each cylinder being adapted to contain both liquid and air under compression, an auxiliary piston separating the liquid from the compressed air, pistons operable in one direction by said block, means for causing liquid to resist the movement of said pistons, partitions between said air and auxiliary pistons, said partitions having ports therethrough, and means for gradually increasing resistance of the liquid against 25 30 35 said pistons.

In witness whereof, I have hereunto set my hand and seal at Indianapolis, Indiana, 40 this 31st day of July, A. D. nineteen hundred and twenty-two.

BYRAM S. DICKERSON. [L. S.]
